PEDIATRIC URINARY DRAINAGE BAG OR SIMILAR ARTICLE

Frank William Stevens, Rutherford, and Samuel Dochung
Han, Leonia, N.J., assignors to Becton, Dickinson and
Company, East Rutherford, N.J.

Filed June 18, 1968, Ser. No. 12,409

Term of patent 14 years

Int. Cl. D24—04

U.S. Cl. D83—1 U

FIG. 1 is a front elevation view of a pediatric urinary drainage bag embodying our new design;

FIG. 2 is a side elevation view thereof; and

FIG. 3 is a rear elevation view thereof.

We claim:

The ornamental design of a pediatric urinary drainage bag or similar article, substantially as shown and described.
